Letters Patent No. 349. - Dated Feb 4, 1851.

The Schedule referred to in these Letters Patent and making part of the same.

To all to whom these Presents shall come:

Be it known, that

I, Samuel A. House of Mechanicville, in the County of Saratoga and State of New York, have invented or produced, a new design of parlor stove front, and I do hereby declare that the following is a full, clear and exact description of the same, reference being had to the annexed drawing, making a part of this specification.

The ornamental design of my stove consists of arabesque figures a, a, rosettes b, b, and eagle at the top moulding, &c.

Dec. 349

2

What I claim as new and desire to secure by Letters Patent, is the design of Stove flue, substantially the same as herein described and represented.
